Primary Examiner — Selina Sikder*(74) Attorney, Agent, or Firm* — KNOBBE MARLENS
OLSON & BEAR LLP(57) **CLAIM**

The ornamental design for a table lamp control unit as shown and described.

DESCRIPTION

FIG. 1 is a top, left, rear perspective view of a table lamp control unit.

FIG. 2 is a top, right, front perspective view thereof.

FIG. 3 is a bottom, right, front perspective view thereof.

FIG. 4 is a right side view thereof.

FIG. 5 is a top view thereof; and,

FIG. 6 is a bottom view thereof.

The broken lines of equal length in the drawings depict features of the table lamp control unit that form no part of the claimed design.

1 Claim, 3 Drawing Sheets(56)
